TUBULAR AMPOULE CLOSURE

Marshall L. Lockhart, Rutherford, N. J.

Application April 1, 1946, Serial No. 658,670

5 Claims. (Cl. 128—220)

1

This invention relates to a structurally and functionally improved closure and in its more specific aspects aims to provide a closure or stopper particularly intended for use with ampules or similar containers for medicaments which are to be injected into tissues by a hypodermic needle.

This application is a continuation-in-part of the prior application which resulted in U. S. patent on Hypodermic Syringe No. 2,410,351 of October 29, 1946. Also, the present application is a continuation in part of my prior application on Stopper for Hypodermic Syringe Ampule, filed April 21, 1945, Serial No. 589,564, now abandoned.

In the practice of medicine, it is frequently necessary to resort to hypodermic injections. Certain of these are of the intravenous type. Most of them are of the subcutaneous and intermuscular type. In other words, the medicament which is to be injected should not be expressed into a vein or large blood vessel. Therefore, correct medical technique has called, in such type of injections, for the piercing of the skin and underlying tissues by a hypodermic needle to a proper depth. Thereupon, the practitioner has endeavored to ascertain whether the cannula has pierced through to a blood vessel. Such piercing has been evident by a flow of blood through the bore of the cannula and outwardly of the same to a point where it might be observed by the practitioner. If the needle tip extends into a vein, then the physician or person administering the hypodermic should withdraw the same and repeat the entire operation in a different locale so that the needle would not extend into a blood vessel. Only after he has assured himself that merely an intermuscular or subcutaneous injection would occur is the medicament expelled through the cannula or needle into the tissues.

Where ampule syringe assemblies have in effect provided a sealed chamber, it has been extremely difficult for the practitioner to determine whether the needle has been extended to a point or at a location such that it was lodged in a vein. As will be understood, with the inner end of the needle extending into, or being in direct communication with, a sealed chamber such as an ampule or the barrel of the syringe, a pressure condition has existed such that blood spurting

inwardly through the bore of the cannula could not flow from the inner end of the same to be visible to the practitioner to warn him that the needle had lodged in a vein.

With this in mind, the present invention aims to provide a closure or stopper for association with a hypodermic syringe barrel or ampule and by means of which an aspirating action may be effected. Thus, by employing such a closure as part of the hypodermic syringe assembly, it will be feasible for the practitioner to quickly determine whether or not the needle is properly disposed in the tissues, or in other words, not in a vein. This will be because with an aspirating type of closure it will be feasible to vary the pressure conditions in an otherwise pressure-stable chamber or container so that if the needle is lodged in a vein a certain amount of blood may readily flow through the bore of the cannula to be visible to the practitioner.

A further object is that of providing a closure which may embody one of a number of different designs such that it is capable of ready association with an ampule or the barrel of a syringe and which closure may be operated to cause an aspirating effect to result without substantially prolonging the over-all period of hypodermic injection.

A further object is that of providing a stopper or closure which will embody a simple design and structure capable of operating under virtually all conditions governing hypodermic injection technique and which closure may be manufactured in quantities at nominal figures by automatic machines and methods.

With these and other objects in mind, reference is had to the attached sheets of drawings illustrating practical embodiments of the invention, and in which:

Fig. 1 is a sectional side view of a part of a syringe assembly and showing one form of closure in association therewith;

Fig. 2 is a similar view of an ampule, the medicament of which is maintained in position by means of a closure constructed in accordance with the present teachings;

Fig. 3 is a fragmentary sectional view of a cylinder barrel and showing an alternative form of closure plug in association therewith;

Fig. 4 is a sectional side view of an ampule with

still another form of closure associated therewith and also showing a portion of a syringe in operative relation with respect thereto; and

Fig. 5 is a sectional side view of a single-ended ampule, its end being sealed by a closure of the present type.

In Fig. 1, there has been shown one unit or barrel of a hypodermic syringe assembly. This may include a body 15 in the form of a cylinder and conveniently constructed of plastic material. A boss 16 may project from this body and serve as a mounting for a double-ended needle 17. A plunger or thrust portion 18 conveniently extends rearwardly within the barrel of body 15 to a point short of its inner end. As shown, this portion is concentrically disposed with respect to and spaced from both the adjacent needle body as well as the inner face of the barrel 15. The inner or rear end of the body may be provided with extensions or flange portions 19. To supplement the finger-engaging parts thus provided, a metallic plate or collar 20 may encircle the barrel 15 and lie in contact with the face of the portions 19.

A syringe such as the foregoing should be provided with a closure such that its interior will be maintained in clean condition. This closure may also serve as an actuator for an ampule to be associated with the syringe. In accordance with the present teachings, the closure may include a body 21, preferably formed of rubber, and hollowed out and recessed to provide what might be termed a chamber portion 22. The end of this portion is closed by a relatively thin part of the body 21 to provide a bowed diaphragm portion 23. A flange 24 may extend from the body 21 and lie in contact with the inner face of the barrel bore adjacent the end of the same. With the parts thus disposed, it is obvious that the barrel will be effectively sealed against the entrance of foreign material.

In using a syringe of this type, the physician or technician will determine the locale of the injection and will thereupon exert an axial thrust upon the assembly such that the outer end of the needle 17 will pierce the skin and underlying tissues. In thus moving the parts, the second and third fingers may underlie the flange portions 19 and plate or collar 20. The thumb may press against the outer face of the body 21. With the closure 21 in position, it is obvious that a sealed chamber is provided by the barrel 15 with the needle embedded in the tissues. Therefore, a condition is present which would usually prevent a seepage of blood through the bore of the needle and from its inner end, even if the outer end of the needle were lodged in a vein.

However, due to the diaphragm portion 23 of the closure, it is feasible to exert an aspirating action. In other words, the diaphragm 23 may be flexed by the thumb or otherwise. Incident to such flexing, the pressure within the barrel 15 will be varied. Accordingly, if the needle 17 be disposed within a vein, blood may in limited quantities be discharged from the inner end of the needle within the barrel. Such discharge of blood will be readily visible to the physician or other technician making the injection. If such flow occurs, it will be apparent that the needle is lodged in the vein and that it should be withdrawn and a second piercing of the tissues effected before medicament is discharged.

If, in response to the aspirating action of the closure 21, no flow of blood occurs, then such closure may be removed and an ampule filled with

medicament may be disposed within barrel 15. Conveniently, the closure 21 is applied to or mounted upon the outer end of such an ampule which may thereupon be freely projected with respect to the syringe barrel as shown in Fig. 1. Such projection will result in a piercing of the usual ampule closure by the inner end of the needle. Continued projection of the ampule will cause its stopper or closure to come into contact with the plunger portion 18, thus causing the stopper to act as a piston. This will serve to express medicament through the needle bore and into the tissues of the patient. After such injection has once been made, the needle may be withdrawn from the tissues and the syringe assembly discarded. Otherwise, after such withdrawal, the parts may be cleaned and sterilized so that they may be reused.

In Fig. 2, an ampule such as is usable with the parts of the syringe assembly shown in Fig. 1 has been illustrated. In that view, the numeral 25 indicates the ampule body formed of glass or other suitable material and which body is conveniently provided with a central, transverse, and imperforate partition 26. Medicament indicated at 27 may fill one of the compartments of the ampule. Adjacent thereto, a syringe plunger portion 18 and a needle 17 have been shown. In this form of construction, it is not contemplated that the closure body 21 as illustrated in Fig. 1 will be employed for the aspirating action. Rather, the closure associated with the ampule will perform this function. However, the closure body 21 may be applied to the free end of the ampule or by inserting the collar portion 24 into the bore at the outer end of such ampule. This will provide a bearing portion suitable for engagement with the thumb of the operator without it being necessary that his thumb come into contact with the ampule edge.

The closure in Fig. 2 has been indicated by the reference numeral 28. Its body is formed preferably of rubber and may present on its outer surface a series of annular ring or rib portions 29. The body is extended, as indicated at 30, to project materially beyond the end of the ampule. This extended portion, which functions as a diaphragm or bulb part, may terminate in a relatively flat surface 31. The area of this surface is preferably sufficiently great so that as the ampule is inserted into the bore of the barrel, the inner pointed end of the needle will be bound to contact the surface 31 even if such needle end is displaced to one side of the axis of the assembly.

As will be apparent, with the projection of the ampule into the cylinder barrel, the pointed end of the needle will contact the flat surface 31 and continued projection will cause that needle end to pierce this surface and extend into the medicament body 27 contained within the ampule. Further projection will cause the plunger portion 18 to contact the surface 31. Either at this time or previously, the needle will have been injected into the patient. If now, the doctor or technician causes the ampule body 25 to be slightly reciprocated with respect to the other portions of the syringe assembly, it is obvious that he will flex or squeeze and re-establish the bulb or diaphragm portion 30. Consequently, an aspirating action will result. Therefore, if the outer end of the needle 17 be in a vein, this will be evidenced under the aspirating action aforescribed by a drop or so of blood emerging from the inner end of the needle. If aspiration fails to develop such a showing, then the reciprocation of the ampule

may be discontinued and the latter may be projected. Under such circumstances, the plunger portion 18 will displace the closure body 28 rearwardly. This will result in the latter functioning as a piston to express the medicament through the bore of the cannula 17 to thus result in an injection.

In the form of construction shown in Fig. 3, substantially the same structure is present, as has been illustrated in Fig. 1. However, in such Fig. 3, the body of the closure 32 has its diaphragm portion pierced or recessed to mount a button or extension 34. The outer face of the latter may be convex and this extension may be formed of rubber which may be of the same grade or harder than that which forms the body 32. In any event, an actuating portion is provided by this structure which will permit of the flexing of the diaphragm 33 with minimum effort. Such flexing may be resorted to throughout a greater range as a consequence of the extension 34 and accordingly a somewhat magnified aspirating action will result. This is desirable in the case of long large bore needles having large volumes. In this structure, an end closure for a syringe barrel has been shown as mounting the closure. Such closure might, if desired, be mounted by the end of an ampule, as in Fig. 2.

In the form of construction shown in Fig. 4, a double-ended ampule has again been illustrated. The outer ampule compartment is sealed by a closure body 35 which is internally recessed as in the constructions heretofore described and terminates in an end wall 36, which serves as a flexing portion. This end wall may be projected and retracted by the plunger portion 37 of a syringe part 38, provided with a bore 39 to receive a needle (not shown). As illustrated, the side walls of the body 35 at points adjacent the end wall 36 are of a diameter less than the interior diameter of the ampule. Therefore, sufficient space exists to permit the end wall 36 to be retracted and then to project itself without the body 35 moving with respect to the ampule 25. Accordingly, an aspirating action is achieved. In any event, it will be understood that, due to the proportions of the closure 35, a sufficiently rigid structure is presented such that a piercing of the end wall 36 may be effected by the inner end of the needle as the ampule is projected into the holder.

The structure illustrated in Fig. 5 shows a single-ended ampule 25' filled with medicament and having its outer end closed by a stopper constructed in accordance with the present teachings. This stopper includes a body 28' with a diaphragm portion 30' which extends beyond its mouth. As taught in my afore-identified application for patent, this portion may be pierced by the needle 17' and may be flexed by the plunger portion 18'. In this manner, an aspirating action is achieved.

Thus, among others the several objects of the invention as specifically afore-noted are achieved. Obviously, numerous changes in construction and the rearrangement of the parts might be resorted to without departing from the spirit of the invention as defined by the claims.

I claim:

1. A closure by means of which aspiration may be effected when it is applied to a tubular member forming a part of a syringe assembly, said closure including a rear part—the outer face of which is disposable in sealing engagement with the bore face of said tubular member—and an integral forward part disposable beyond the end

of said member, said closure being formed of resilient material and having a recess extending from the end of the rear part through to the forward part thereof, said recess being enlarged within the area of said latter part to provide a bulb-chamber and a diaphragm integral with said forward part and defining the outer face of the same as well as that of said chamber.

2. A closure for use in connection with the open end of a tubular member forming a part of a syringe assembly, said closure including a body to be disposed within the bore of said member to intimately engage the surface thereof, a resilient and collapsible extended portion forming a part of one end of said body and to project beyond the end of the tubular member mounting said closure, an imperforate and flexible wall across the outer end and forming a part of said extended portion, such portion and body being formed with a recess extending from the inner face of said end wall through to that end of the body opposite to that at which said extended portion is provided, said recess being enlarged within the area of said extended portion and adjacent said end wall to provide a bulb-chamber, said imperforate end wall being adapted for reciprocation with respect to said body to extend and collapse said portion and decrease and increase the area of said bulb-chamber to create a condition of subatmospheric pressure within the recess and a member to which said closure is applied.

3. A resilient closure to seal the open end of a medicament-containing tubular ampule, said closure including a body to be disposed within the ampule bore to intimately engage the surface thereof and slidably cooperate as a piston with said bore, a resilient and collapsible extended portion forming a part of one end of said body and to project beyond the end of the ampule mounting the closure, an imperforate and flexible end wall across the outer end of said extended portion, such portion and body being formed with a recess extending from the inner face of said wall through to that end of the body opposite to that at which said extended portion is provided, said end wall and portion being of less diameter than said body and said imperforate wall being adapted for penetration by a needle and engagement by a thrust portion, whereupon said portion will be collapsed with respect to the closure body and may thereupon extend with respect to that body as the resiliency of the extended portion reestablishes the position of the wall, such projection causing the creation of a subatmospheric condition within the recess and an ampule mounting said closure.

4. A resilient closure to seal the open end of a medicament-containing tubular ampule, said closure including a body to be disposed within the ampule bore to intimately engage the surface thereof and slidably cooperate as a piston with said bore, a resilient and collapsible extended portion forming a part of one end of said body and to project beyond the end of the ampule mounting the closure, an imperforate and flexible end wall across the outer end of said extended portion, such portion and body being formed with a recess extending from the inner face of said wall through to that end of the body opposite to that at which said extended portion is provided and being enlarged within the area of said portion and adjacent said wall to provide a bulb-chamber, said end wall and portion being of less diameter than said body and said imperforate

wall being adapted for penetration by a needle to extend into said bulb-chamber, said end wall being moreover adapted for engagement by a thrust portion which when so engaging the end wall will cause a retraction of the latter with respect to the closure body and—upon release of said thrust portion—a projection of the end wall, as the resiliency of the extended portion re-establishes the position of the wall, such end wall projection causing an expansion of the bulb-chamber to create a subatmospheric condition within the recess and an ampule mounting said closure.

5. A resilient closure for application to the open end of a tubular barrel forming a part of a syringe assembly, said closure including a headed body, a circular flange forming a part of said body and of a diameter to sealingly engage the bore face of said barrel, the head of said body having a diameter greater than that of said flange and being formed with an enlarged recess communicating with the space defined by said flange, an outwardly bowed flexible and resilient wall defining the outer end of said

5
10
15
20

recess and said wall—under pressure applied to this outer face—acting as a diaphragm to be flexed inwardly and—upon the release of such pressure—moving outwardly to create a condition of subatmospheric pressure within said chamber and within a barrel to which such closure is applied.
